UNITED STATES PATENT OFFICE.

WILLIAM NESTLER, OF NEW YORK, N. Y., ASSIGNOR TO LENDING PASSEMENTERIE CO., INC., OF NEW YORK, N. Y.

DESIGN FOR GIMP.

Application filed June 18, 1924. Serial No. 9,897. Term of patent 7 years.

To all whom it may concern:

Be it known that I, WILLIAM NESTLER, a citizen of Germany, residing in the borough of Manhattan, city, county, and State of New York, have invented a new, original, and ornamental Design for Gimp, of which the following is a specification, reference being had to the accompanying drawing, forming part thereof.

The figure is a face view of a portion of gimp, showing my new design.

I claim:

The ornamental design for gimp as shown.

WILLIAM NESTLER.

Witnesses:—

GEO. W. MIATT,
NATHAN LEUNCER.
